UNITED STATES PATENT OFFICE

2,546,937

APPARATUS FOR DELIVERING A FLUID
INTO A FURNACE

John J. Wyandt, Canton, and James K. McKelvey,
Massillon, Ohio, assignors to Republic Steel
Corporation, Cleveland, Ohio, a corporation of
New Jersey

Application January 7, 1949, Serial No. 69,752

4 Claims. (Cl. 266—34)

1

The present invention relates generally to the art of handling and mixing fluids and is more particularly concerned with novel and very useful and economical apparatus for delivering a fluid in jet form into contact with a relatively large body of molten metal.

This invention is addressed to the problem of delivering oxygen into molten steel in an electric furnace or an open hearth furnace. Despite the advantages of increased production rates and fuel savings to be gained through the use of elemental oxygen in such steel processing furnaces, the operation has not, to the best of my knowledge, been successfully carried out on a commercial scale prior to the present invention. This failure of the art to use oxygen and obtain the advantages which it offers is attributable in substantial part to the fact that no suitable lance means has heretofore been developed. One of the principal shortcomings of the lances of the art has been their inability to withstand for any reasonable length of time the effects of the high temperatures obtaining in steel processing furnaces. Suitable means of supporting and positioning the lances has also been a problem in this connection.

These difficulties can, by virtue of this invention, now be fully met and disposed of in an economical and very practical manner. Furthermore, the devices hereof are easily constructed and capable of serving effectively over heretofore impossibly long periods in close proximity to high temperature masses. Additionally, when maintenance, replacement or repair is necessary upon these devices, it can be effected easily and quickly and at small material and labor cost. The supporting structure for the lance of this invention, furthermore, is so designed and constructed that it may be secured directly to the furnace in a temporary or permanent manner and the lance may be disposed at any of a number of levels with respect to the furnace melt by adjustment of such supporting structure, the security of the lance being assured at all times regardless of its position. The advantages of convenience and safety consequently are uniquely combined in this structure of our invention.

Upon consideration of the drawings accompanying and forming a part of this specification and the following detailed description of the present invention in a preferred form, those skilled in the art will detect still further desirable characteristics and advantages of this invention and will gain a clearer understanding of its salient features.

2

Referring to the drawings,

Figure 1 is a fragmentary, side elevational view partly in section of a lance and lance supporting structure embodying the present invention;

5 Figure 2 is an elevational view taken on line 2—2 of Fig. 1;

Figure 3 is a fragmentary, enlarged side elevational view partly in section of the lance shown in Fig. 1; and

10 Figure 4 is an enlarged fragmentary cross sectional view of the leading or nozzle end of the lance of Fig. 1.

The illustrated lance comprises a nested tube assembly which includes an inner tube 10 having an externally threaded inlet end 11, an intermediate tube 12 surrounding the tube 10 over a portion of its length but stopping short of the ends thereof and having an externally threaded end portion 13 adjacent to the inlet end 11 of the inner tube. An outer or casing tube 15 extends a short distance beyond the outlet end of tube 10 and terminates at its other end short of, but near, the threaded end of tube 12. Tube 10 may be connected to a suitable source of oxygen (not shown) by means (also not shown) such as a conduit and coupling joined to threaded end 11. The threaded end of tube 12 may be connected to a stuffing box (not shown) of conventional form to allow for expansion of the inner tube under the influence of the heat of the furnace in which the lance is used.

Adjacent to their outlet ends, tube 10, 12 and 15 are turned off at an angle of about 60 degrees to their longer sections so that oxygen may readily be delivered generally downwardly into a molten bath while the major portion of the lance is disposed substantially horizontally.

40 Adjacent to the threaded end of tube 12, an inlet opening 17 is provided through which cooling water may be delivered when the lance is in use, a short length of pipe 18 being welded to the tube around said opening to facilitate connection of tube 11 to a suitable source (not shown) of cooling fluid under pressure. An outlet opening 20 for the cooling water is in turn provided in tube 15 adjacent to its cold end and again a pipe 21 is secured to tube 15 around said opening to facilitate transference of water from within the lance to a receiving vessel (not shown).

45 50 Spacers 25 and 26 comprising metal lugs are tack welded to tube 10 and 12, respectively, and bear against opposing surface portions of tubes 12 and 15, respectively. The said tubes thereby are held in uniform spaced relation throughout their lengths, tube 12 and 15 being disposed apart

approximately twice as far as tubes 10 and 12. In order that the flow of cooling water through the lance can be as free and rapid as necessary to protect the lance from the heat to which it ordinarily will be subjected in use, spacers 25 and 26 are limited in size and number as far as possible and are arranged in staggered relation.

At the nozzle end of tube 15 a copper plug 30 having a threaded axial aperture 31 is disposed, closing the opening defined in said end of the tube and receiving in the inner end of aperture 31 the outlet end of pipe 10. Plug 30 is brazed to the tubes 10 and 15, the latter bearing against an annular shoulder defined by the outer peripheral portion of the plug. A replaceable tube 35, preferably of steel but suitably of other metal of sufficiently high melting point for the purpose, such as copper, is secured to the nested tube assembly, having an externally threaded end portion 36 screwed into aperture 31 of plug 30. This nozzle tube 35 is preferably of the same internal diameter as tube 10 and cooperates therewith to define a substantially continuous passageway of uniform diameter. The outside surface of the leading or nozzle portion of the nested tube assembly, as well as of tube 35, is provided with a coat 36 of asbestos or refractory cement for heat insulating purposes.

The lance supporting structure mentioned above comprises a bracket 40 having a bifurcated lower portion 41 and a transversely extending, outwardly projecting flange 43 on its upper portion. Flange 43 is apertured to receive pins or bolts 44 secured, as by welding, to the flange so that the bracket may be fastened or hung temporarily on a furnace. On the opposite side of the bracket from flange 43 are a pair of spaced apart, opposed, longitudinally extending flanges 45, the lower portions of which are provided with a plurality of slots 48 registered in pairs to receive a pin 50 serving as an axle for a grooved pulley wheel 51 on which the lance may bear, as shown in Figs. 1 and 2. Thus, the lance may be run forward or drawn back from the furnace without lifting effort on the part of the attendant, and when the position of the lance is to be shifted, wheel 51 with its axle 50 may be withdrawn from its original position and placed in another pair of registered apertures to provide the desired increase or decrease in elevation of nozzle tube 35, the lance as a whole being retained in the bracket and shifted from one position to another as wheel 51 is moved to obtain the desired results.

Having thus described the present invention so that those skilled in the art may be able to understand and practice the same, we state that what we desire to secure by Letters Patent is defined in what is claimed.

What is claimed is:

1. Apparatus for delivering a fluid into contact with molten metal in a furnace comprising a nested tube assembly including an inner tube communicating with a source of said fluid under pressure and having a discharge end, and an intermediate tube and an outer tube communicating with each other adjacent to said discharge end and with a source of cooling fluid under pressure and a discharge line respectively, said discharge end of the inner tube being within the outer tube and outside the intermediate tube, a plurality of spacers between the intermediate tube and the inner and outer tubes and holding the tubes in predetermined, substantially uniform, spaced relation throughout the length of said assembly, and a nose piece bearing against and closing the end of the outer tube, said nose piece having an axial portion extending into said outer tube and having a threaded transverse aperture receiving in fluid-tight engagement the discharge end of said inner tube.

nose piece bearing against and closing the end of the outer tube, said nose piece having an axial portion extending into said outer tube and having a threaded transverse aperture receiving in fluid-tight engagement the discharge end of said inner tube, and a nozzle tube having an externally threaded end screwed into said threaded aperture to receive fluid from said inner tube.

2. Apparatus for delivering a fluid into contact with molten metal in a furnace comprising a rigid nested tube assembly including an inner tube communicating with a source of said fluid under pressure, said inner tube having a discharge end portion defining an included angle of about 120° with the principal axis of the tube, an outer tube of substantially increased diameter having an end portion enclosing the discharge end of the inner tube and extending at an angle of about 120° to the principal axis of the outer tube, an intermediate tube communicating with the outer tube adjacent to said discharge end and with a source of cooling fluid under pressure, said intermediate tube having an end portion terminating within the outer tube and adjacent to the discharge end of the inner tube and defining an angle of about 120° with the axes of the principal portions of said other tubes, a plurality of spacers disposed between and engaging said intermediate and inner and outer tubes, a cylindrical nose piece welded to and closing the end of the outer tube, said piece having a threaded axial aperture and an axially extending portion of reduced diameter receiving in fluid-tight engagement the discharge end of said inner tube, and a rigid nozzle pipe having an externally threaded end screwed into said axial aperture to receive fluid from said inner tube.

3. Apparatus for delivering a fluid into contact with molten metal in a furnace comprising a tubular lance through which said fluid may be conducted to said molten metal, means for supporting and positioning the lance relative to said metal including a vertically adjustable rotatable wheel on which the lance may run and a frame straddling and supporting said wheel, and means associated with said frame for securing the frame to the said furnace in position for delivery of fluid through the lance into molten metal in the furnace.

4. Apparatus for delivering a fluid into contact with molten metal in a furnace comprising a nested tube assembly including an inner tube communicating with a source of said fluid under pressure and having a discharge end, and an intermediate tube and an outer tube communicating with each other adjacent to said discharge end and with a source of cooling fluid under pressure and a discharge line respectively, said discharge end of the inner tube being within the outer tube and outside the intermediate tube, a plurality of spacers between the intermediate tube and the inner and outer tubes and holding the tubes in predetermined, substantially uniform, spaced relation throughout the length of said assembly, and a nose piece bearing against and closing the end of the outer tube, said nose piece having an axial portion extending into said outer tube and having a threaded transverse aperture receiving in fluid-tight engagement the discharge end of said inner tube.
